PHOTOGRAPHIC PRINTING APPARATUS

Filed Dec. 24, 1927

UNITED STATES PATENT OFFICE

VLADIMIR K. ZWORYKIN, OF SWISSVALE, PENNSYLVANIA, ASSIGNOR TO WESTINGHOUSE ELECTRIC & MANUFACTURING COMPANY, A CORPORATION OF PENNSYLVANIA

PHOTOGRAPHIC PRINTING APPARATUS

Application filed December 24, 1927. Serial No. 242,346.

My invention relates to photographic printing apparatus, and it has particular relation to apparatus for use in printing one moving-picture film from another, with either an enlargement or reduction in dimensions.

Machines of many different types have been proposed for use in the continuous printing of moving-picture film positives from a negative, after the latter has been edited, and the various portions thereof arranged in predetermined sequential order. Substantially every machine of the character just mentioned comprises a plurality of rotary film magazines, certain of which accommodate the negative film and others of which carry the positive film before and after exposure.

In order that the positive and negative films shall travel through the machine at the proper relative speeds, it has been customary, in the past, to interconnect the positive and negative-film magazines by suitable gearing for transmitting motion therebetween.

Film-printing machines of the type in which gears are utilized to transmit motion between the several moving parts thereof have given a fair degree of satisfaction in the reproduction of moving-picture films of the usual type, but, in general, fail to satisfactorily reproduce films of the type wherein the pictures are accompanied by a marginal portion representative of sounds that were photographically recorded on the negative.

The variation in the relative rates of positive and negative film travel through printing machines, caused by the back-lash in the gear-trains, or by the slippage, if belt connections are used, although insufficient to prevent the proper printing of the picture-portions of the film, is still enough to seriously interfere with the reproduction of the extremely minute film-density variations representing sound. If the film is to be reduced in width and length in the printing operation, the utmost fidelity in reproduction is imperative, a fact which has heretofore prevented the satisfactory reduction in size of commercial talking-picture films for use in projectors of the home type.

It is, accordingly, an object of my invention to provide an apparatus for the general purpose of film printing, the said apparatus being adapted to either enlarge or reduce motion-picture films with absolute fidelity. 55

Another object of my invention is to provide film-printing apparatus wherein variation between the rate of travel of the positive and the negative film is prevented with certainty. 60

Another object of my invention is to provide film-printing apparatus especially adapted for the reproduction of motion-picture films of the type which carry a sound record in addition to the picture record. 65

Another object of my invention is to provide a film-printing machine particularly adapted for the reproduction of photographic sound records.

Another object of my invention is to provide a film-printing machine in which gear-trains are not relied upon to transmit motion between the mechanism for advancing the positive film and the mechanism for advancing the negative film. 70 75

Another object of my invention is to provide a film-printing machine that shall be capable of making a continuous positive, greatly reduced in dimensions, from a negative film of the usual commercial size. 80

In one embodiment of my invention, I attain the aforementioned objects by employing, as film-advancing and film-supporting devices, a plurality of toothed wheels mounted in spaced relation on a rotatable shaft. 85 Two of the wheels are of large diameter and two are of smaller diameter, the latter pair being affixed to the shaft intermediate the large wheels. The large film is fed from a magazine over the pair of large wheels, while the small film is fed over the small wheels in a similar manner. The shaft is preferably rotated by a small motor, and the film magazines are geared thereto. 90

A source of light and a lens system are so disposed that light may be transmitted through the negative film to fall upon the unexposed sensitive surface of the positive film. The light source, when a reduction in film size is to be made, is positioned exteriorly of 95 100

the large wheels over which the negative film is fed, and the light therefrom, passing through the negative film, falls upon the surface of the unexposed film carried over the 5 smaller wheels. If the device is to be used for enlarging, the negative film is fed across the small wheels and the positive film across the large wheels, the light source being so re-positioned that the negative film passes between it and the positive film.

In order to avoid confusion, I have chosen the term "negative" as characterizing any film which has been exposed and developed, irrespective of whether the film is of the so-called "positive" or "negative" type, and I have chosen the term "positive" to characterize the film which is reproduced by enlargement or reduction from the "negative" film.

Among the novel features of my invention 20 are those partly set forth in the appended claims. The invention itself, however, both as to its organization and its method of operation, together with further objects and advantages thereof, will best be understood 25 from a consideration of the following description of certain specific embodiments, taken in connection with the accompanying drawings, in which:

Figure 1 is a front elevational view of a 30 portion of a film-printing machine comprising a preferred embodiment of my invention.

Fig. 2 is a sectional view, taken along a line corresponding to the line II-II of Fig. 1.

Fig. 3 is a plan view of the guide elements over which the film passes.

Fig. 4 is a sectional view, taken along a line corresponding to the line IV-IV of Fig. 3.

Fig. 5 is a diagrammatic view, partly in section, of a modified form of my invention.

Fig. 6 is a view, in perspective, of a portion of the optical system comprised in the apparatus illustrated in Fig. 5.

The apparatus shown in Figs. 1 and 2 comprises a shaft 1 on which is mounted a gear-wheel 2 that meshes with a similar gear-wheel 3 actuated by a prime mover 4, such as an electrical motor. Two discs or wheels 5 and 6 are mounted on the shaft, for rotation thereby, and are spaced apart a distance slightly less than the width of a film of the commercial type, namely, approximately 35 millimeters. The discs 5 and 6 are provided 50 with peripheral projections 7 which are properly spaced apart to register with the marginal perforations in the usual motion-picture film.

Two similar, though smaller, discs 8 and 10 are mounted on the shaft 1, intermediate the large discs 5 and 6, and are spaced apart a distance slightly less than the width of the film usually utilized in projectors of the home type, namely approximately 16 millimeters.

A storage magazine or spool 11 is mounted

above the shaft 1 and accommodates a negative film 12 which is to be reproduced. The film is withdrawn from the magazine 11 by the rotation of a similar magazine 13 and, in its travel between the two magazines, it passes over a guard plate 14 mounted adjacent the peripheries of the toothed wheels 5 and 6. The guard plate, which is shown in detail in Figs. 3 and 4, is preferably slightly wider than the film 12 and has an opening 15 of H- 75 shape extending therethrough.

The toothed discs 5 and 6 project a slight distance through the opening 15 and register with the marginal perforations of the film 12, serving to assist in advancing the film in its 80 travel between the two magazines and to prevent it from slipping.

Two magazines 16 and 17 are provided to accommodate a positive film 18 before and after exposure, and the film 18, in its travel 85 between the magazines, passes over a guard plate 20 positioned adjacent the small discs 8 and 10, through which plate extend small peripheral portions of the said discs. The guard plate 20 is similar in form to the plate 14, although smaller in dimensions.

A light source 21, preferably an incandescent lamp, is adjustably supported adjacent to the peripheries of the large discs, and the light therefrom is concentrated into a beam 25 by a lens system, exemplified by the lens 22, which beam falls upon the negative film as it passes over the central opening in the guard plate 14.

A second lens system, exemplified by the 100 lenses 23 and 24, is arranged intermediate the guard plate 14 and the guard plate 20 associated with the small discs 8 and 10 and serves to form a reduced image of the illuminated portion of the negative film on the positive 105 film 18.

Although not so shown in the drawings, it is necessary that the entire positive film shall be thoroughly protected against all light except that which comes from the illuminated section of the negative film, and, to that end, the entire apparatus, including the light source 21, is preferably enclosed in a 110 light-tight box.

In the operation of the apparatus shown 115 diagrammatically in Figs. 1, 2, 3 and 4, the film 12 travels in the direction indicated by the arrows, while the film 18 travels in the opposite direction. The reason for this opposite travel lies in the fact that the lens system, comprising the lenses 23 and 24, forms an inverted image of the illuminated portion of the film 12 on the film 18. If the films were to travel in the same direction, it would be necessary to repeat the printing operation twice in order to obtain a film suitable for projection.

The ratio between the speed of advance of the negative film and the speed of advance of the positive film through the machine is 130

the same as the ratio existing between the circumference of the large discs and the circumference of the small discs, since both pairs of discs are rotated in unison by a single shaft.

5 Hence, if it is desired that the positive film shall be just one-half the length of the negative film from which it is printed, the circumference of the small discs is made one-half as long as the circumference of the large discs, and the lens system is arranged to form 70 an image of the illuminated portion of the negative film on the positive film which is one-half the size of the said portion.

When projecting the reduced positive, if 15 it is passed through the apparatus at one-half the normal speed at which the large-size film is passed through similar apparatus, the same number of separate pictures, or frames, will be thrown upon the screen per second 20 as is the case with the large film. At the same time, the film-density variations representative of sounds will travel at the proper speed through the sound-reproducing apparatus, which apparatus usually comprises a 25 photo-electric cell and a thermionic amplifier, to re-create the sounds as recorded on the original film.

A modified form of my invention is illustrated in Figs. 5 and 6, in which figures the 30 elements analogous to those of Figs. 1 to 4 are numbered similarly.

In the alternative form, the reduced image of the illuminated portion of the film is caused to pass around and below the shaft 1 35 by using a double prism 25. The prism, which is more clearly shown in Fig. 6, has a shape which might be termed "double rhomboidal", the faces 26, 27, 28 and 30 thereof being arranged at appropriate angles with 40 respect to a line which passes through the light source 21 and the center of the shaft 1. The image is reflected internally of the prism and falls on the film 18 just as though the shaft were not present.

45 It lies within the scope of my invention to support the film 18 on the small discs, nearest the points on the large discs at which the film 12 is supported and advanced. In such event, it is necessary that the intermediate 50 lens system 23-24 be such that it forms an erect image of the illuminated portion of the negative film on the positive film. A lens system of this type, however, absorbs more light than the systems illustrated, and, for 55 that reason, this further modification of my invention is not so desirable in practice.

It also lies within the scope of my invention to reverse the relative positions of the positive and negative films and also of the 60 light source, in order that a small film may be enlarged to the dimensions of films of commercial type. This modification, being believed sufficiently obvious, is not illustrated.

65 The principal advantage of my improved

film-printing machine lies in its ability to reproduce, with exact fidelity, the very smallest gradations of the sound record; and to reproduce them in a smooth, continuous, and uninterrupted manner. I have been unable 70 to detect, by ear, any difference in quality between the sound reproduced from a film made by utilizing my improved printing machine and the sound reproduced from the original film.

There is no back-lash, such as is present 75 when gears are used, and there is but little possibility of slippage between the films and the rotating discs.

Inasmuch as the positive film cannot move 80 relative to the negative film except at the rate determined by the respective circumferences of the several pairs of discs, the reduced sound record is a microscopically faithful 85 replica of the original.

In addition, my improved printing apparatus is simple in construction and easy to operate. Even after continuous use for many months, the accuracy with which it reproduces picture and sound records is not impaired, since the portions of the device which are subject to wear have little or no influence 90 on the relative speed at which the films are advanced therethrough.

Although I have illustrated and described 95 only two specific forms of my invention, numerous modifications will be apparent to those skilled in the art to which the invention pertains, and my invention is accordingly not to be limited except by the prior art 100 or by the spirit of the appended claims.

I claim as my invention:

1. In a film-printing machine, a plurality of rotatable film-advancing devices having peripheral surfaces modified to cooperate 105 with the marginal perforations in a continuous film, an axial support therefor, a plurality of similar though smaller devices mounted on said axial support intermediate said first mentioned devices, a light source, and means for causing the light from said source to traverse a portion of the space bounded by said devices.

2. In a film-printing machine, a rotatable shaft, a plurality of circular elements mounted thereon in spaced relation and adapted to support and advance a film, and a plurality of similar though smaller elements mounted on said shaft intermediate said first mentioned elements, said second group of elements being adapted to support and advance a film of smaller dimensions than said first mentioned film, in combination with means for illuminating a section of said first mentioned film, and means for casting an image of said illuminated section of said first mentioned film on said smaller film, said image-casting means being disposed within the cylinders of which said circular elements are the bases.

3. In a film-printing machine, a rotatable shaft, a plurality of circular elements mounted thereon in spaced relation and adapted to support and advance a film, and a plurality of similar though smaller elements mounted in said shaft intermediate said first mentioned elements, said second group of elements being adapted to support and advance a film of smaller dimensions than said first mentioned film, in combination with means for illuminating a section of said smaller film, and means for casting an image of said illuminated section of said smaller film on said first mentioned film, said image-casting means being disposed within the cylinders of which said circular elements are the bases.

In testimony whereof, I have hereunto subscribed my name this 15th day of December, 1927.

VLADIMIR K. ZWORYKIN.
